UNITED STATES PATENT OFFICE

WILLIAM C. HIERING, OF NEWARK, NEW JERSEY, ASSIGNEE TO J. E. MERGOTT CO., OF NEWARK, NEW JERSEY, A CORPORATION OF DELAWARE

BAG FASTENER

Application filed December 10, 1927. Serial No. 299,091.

This invention relates to bag fasteners having reference to that class of devices used in securing the sides of a framed bag in closed relation; the term "bag" as herein used includes satchels, purses, pocket-books and like containers of varying sizes and types.

Such bags generally consist of a flexible sack or pouch provided with a pair of metal frames composed of two similar members having straight central portions and angular side elements which are hingedly connected at their extremities.

Fastening devices by which the two frame sides are secured, are preferably raised above the general level of the frame surfaces for convenience of operation and to avoid weakening the frame members; this raised position has resulted in the use of special frames having extensions or widened portions to which the fastening devices are applied and precludes the use of plain continuous channel frames.

Frames for this purpose are preferably made of channel bars of U shaped cross section, the bars being cut to length and bent into the desired shape or are die formed from a flat blank, in either case presenting smooth and level surfaces of uniform appearance and cross section throughout their entire length.

It is therefore the main object of this invention to provide a fastener device which can be applied to plain channel frames without weakening the same and which possesses all the advantages of a special frame, including a highly ornamental appearance.

A further feature is in the provision of a simple, strong and highly effective fastener that can be made and applied to an ordinary channel frame at a moderate cost.

These and corresponding objects are attained by the novel construction and arrangement of parts hereinafter described and shown in the accompanying drawing, forming part hereof, and in which:—

Figure 1 is a perspective view showing the upper portion of a conventional type of bag frame illustrating the application of the invention.

Figure 2 is an enlarged transverse sectional

view taken substantially on line 2—2 of Figure 1.

Figure 3 is an enlarged front elevational view of one of the fastener elements as applied to a frame member, parts being broken away to show the construction. 55

Figure 4 is a longitudinal sectional view taken on line 4—4 of Figure 2.

The frame shown is composed of two plain symmetrical channel frames A and B, respectively front and rear, these channels being equal and uniform in cross section throughout their entire length. 60

As shown in Figures 2 and 3, the rear frame B has at its center an upstanding rigid projection 10, sheared from the top member connecting the two side walls of the frame, constituting a catch and registering with the inner wall of the frame. 65

The top member of this frame is also perforated by elongated slots 11 at equally spaced distances from the catch 10, adjacent the outer wall of the frame, these slots permitting the passage of the flattened loops 12 formed on the lower edges of a doubled plate 75 presenting a front leaf 13 and a rear leaf 14 of larger area, both plates having arcuate profiles.

This plate, when in a flat condition is die cut to produce the loop elements and also 80 registering recesses 15 through both leaves when tightly folded, the recesses acting as clearance spaces as will later be seen.

A torsional spring 16 having an angular tang 17 and flattened bar portion 18 is mounted within the space enclosed by the frame walls, the bar being passed through the loops 12 in which it is tightly engaged and the tang 17 held against the inner wall of the frame, due to the torsion effect of the spring, 90 which same effect being transmitted to the leaves 13—14, forces them forwardly towards the mating member of the frame and at the same time the spring acts as a hinge pin on which the leaves may turn as a unit. 95

These leaves are held together by brazing, soldering or the like, at which time there is secured to the outer larger leaf 14 the rear wall 19 of an arcuate cap 20, preferably presenting a bevelled arcuate outer surface, the 100

front edge being shaped to present a finger grip 21 extending slightly beyond its front wall 22 in which is an arcuate opening 23.

From the foregoing it will be clear that the entire cap and its support may be rocked on the spring 16 as a unit and it will also be apparent that the spring receiving loops might be made directly on the rear edge of the cap wall 19.

10 Fixed on the top element of the mating channel frame A are two rigid lugs 25 having bevelled inner faces and adapted to be engaged by the flat lowermost edges 24 of the cap whereby the frame sides may be held securely together, the cap rising as the edges contact with the lugs to permit them to enter and then spring down to engage their outer sides.

15 For additional security the following device is provided; a hollow sheet metal casing 26 having front and rear walls and an arcuate top, adapted to neatly fit the opening 23 in the cap, is held to the top element of the frame side A by inbent lugs 27 passed through appropriate openings in the top, these lugs reaching from the ends of the casing as will be seen in Figure 4.

20 Rotatably mounted in the side walls of the casing 26 is a latch spindle 32 having a flanged head in which is pivoted a pendant pull handle 28.

25 The stem 29 of the spindle is flattened on two opposite sides, these flattened surfaces bearing against a flat bowed spring 30, its ends being supported on the top element of the channel and held in position by the ends of the casing at points over the lugs 27.

30 The inner end of the spindle terminates in a hook-like latch head 31 enterable into the recess 15 and, by reason of the handle, is rotatable to engage with the catch 10 or disengage therefrom, the hook being held in either of its adjusted positions by the spring 30.

35 It is to be noted that the spindle 32 is mounted in the casing 26, above and clear of the frame A, which is not mutilated or weakened thereby, and provides a convenient and artistic fastener.

40 Although the foregoing is descriptive of the preferred embodiment of the invention, it will be apparent that minor changes may be made in its construction, without the exercise of invention or conflicting with the scope of the claim hereto appended.

45 Having thus described my invention, what I claim as new and desire to secure by Letters Patent, is:

50 In combination, two frame members movable relatively to each other, a spring-actuated, recessed cap mounted on one of said frame members, a casing mounted on the other frame member adapted to be received within the recessed portion of said cap, and 55 a latch stud revolvably mounted in said cas-

ing adapted to have latching engagement with the first named frame member.

This specification signed this seventh day of December, 1927.

WILLIAM C. HIERING.
